UNITED STATES PATENT OFFICE.

HEINRICH RUEF, OF ZURICH, SWITZERLAND.

MIXING MACHINE.

Application filed April 3, 1925. Serial No. 20,432.

To all whom it may concern:

Be it known that I, HEINRICH RUEF, a citizen of the Swiss Republic, residing at Zurich, Switzerland, have invented an Improvement in Mixing Machines, of which the following description, in connection with the accompanying drawings, is a specification, like characters on the drawings representing like parts.

10 The present invention relates to mixing machines having a bipartite mixing drum, one part of which is formed by the trough of a vehicle serving to convey the material on and off, whereby the vehicle has to be moved into a supporting device surrounding the second part of the mixing drum and is turned by said device when the machine operates; thereby a lifting device is rendered superfluous and the repeated handling 20 of the material is avoided.

Mixing machines of this type are known in which the supporting device is mounted in the frame of a driving mechanism arranged opposite the side at which the vehicle enters the machine and having an axle extending through the whole machine; this axle limits the height at which the conveying vehicle can be placed inside the supporting device.

30 This drawback is overcome with the mixing machine according to the present invention in that the supporting device is turnable in outer bearings which do not project into the interior of the supporting device. This arrangement permits in a simple manner such an adjustment of the conveying vehicle in the supporting device that the centre of the rotating system coincides as nearly as possible with the axis of rotation, so that favorable working conditions (small driving power, quiet running and in consequence thereof a better mixing of the material and a smaller wear of the machine) are obtained.

45 Preferably the supporting device is turnable on roller bearings with which circumferential ring-shaped bearing faces cooperate.

50 Several constructional examples of this mixing machine are illustrated on the accompanying drawings, in which:

Fig. 1 shows in a vertical section a first

constructional form of a power driven type of the mixing machine;

Fig. 2 is a section along line II—II in Fig. 1,

Fig. 3 shows a detail in a plan view,

Fig. 4 shows in a vertical section a second constructional form of the power driven type,

Fig. 5 is partly an elevation and partly a section along line V—V in Fig. 4,

Fig. 6 is an elevation of a third constructional form,

Fig. 7 is a side view seen from the left hand side of Fig. 6 and

Fig. 8 is a plan view of Fig. 6.

With the first constructional example (Figs. 1 and 2) the circular body 1 comprises two flanges 2 formed by angle iron which are rigidly connected to each other by means of distancing rods 3 and the trough 4 forming one part of the mixing drum and the two guide rails 5. The latter are fixed with their ends to angle irons 6 which are connected to the flanges 2 in the manner of chords. The circular body 1 is supported on four supporting rollers 7 by the flanges 2; the rollers 7 acting as spur wheels are loosely mounted in pairs on two shafts 8. One of the latter forms the driving shaft and is provided with a fast pulley 9 and a loose pulley 10 and with a gear wheel 8^a cooperating with a toothed rim 1^a of the circular body. The shafts 8 extend beyond the wheels 7 and are mounted in bearings on supporting rails 11 which are arranged in a recess 12 of the ground. On the latter a pair of rails 13 is arranged transversely to the supporting rails 11 and interrupted between the latter within the mixing machine.

On the rails 13 the waggon 14 of the usual construction having a tiltable trough 15, which forms the second part of the mixing machine, is moved towards and away from the mixing machine. The waggon 14 which conveys the material to be mixed, is pushed from the rails 13 into the guide rails 5 of the circular body 1, whereupon the waggon is secured in the required position in the circular body 1. To this end a locking device is provided having a shaft 16 arranged within a tube fixed to the end walls

4' of the trough 4 and mounted in bushes and provided with double armed levers 17 at both ends. One of the two levers 17, to which two links 18 are connected is provided with a handle 17' as is shown in Fig. 1. On the latter a pawl 19 is mounted which by the action of the weight loaded arm 20 is ordinarily pressed into engagement with a toothed segment 21 fixed to the adjacent end wall 4' of the trough 4. The other ends of the links 18 are coupled to levers 22 pivoted to the trough 4 by means of a pin 23. At its free end the lever 22 is provided with an angle iron 24 and an ear 25 standing at right angles to the former. This part serves for fixing the trough 15 of the waggon inserted in the circular body 1 at the respective corner on its angle iron edge from above as well as from outside 20 to the two walls of the trough meeting each other. The four arresting parts 24, 25 adjusted by means of the handle 17' through the intermediary of the two pairs of links 18 and which project above the four corners 25 of the trough 15 secure the waggon 14, which is prevented against lateral displacement by the guide rails 5, in its proper position in the circular body 1 and press the waggon tightly against the guide rails 5. 30 The fixation of the waggon 14 in the circular body 1 may also be effected by utilizing the longitudinal edges of the mould 4 which consists of sheet-iron, preferably by arranging them to project somewhat beyond the edge 35 of the waggon (trough 15) so that they are pressed against the sides of the waggon owing to their elasticity.

The rotation of the shaft 8 by means of the fixed belt pulley 9 causes the rotation 40 of the circular body 1 by the aid of the gear wheels, 8^a, 1^a. The mixing drum formed by the moulds 4 and 15 and the running gear of the waggon turn thereby together with the circular body 1 around the axis 45 of the latter which is central to the whole system. In the trough 4, which is symmetrical with regard to the vertical axis of the waggon two guide blades 26 are arranged in both halves of symmetry for increasing 50 the mixing action, which is further essentially increased by a strainer arranged in the axis of symmetry of the trough 4. Enlargements 28 provided on the longitudinal walls of the mould 4 cause a certain deviation 55 of the material to be mixed from the butt joint between the troughs 4 and 15, similar enlargements may also be provided at the end faces 4'. The mould 4 may also have a spherical shape instead of a cylindrical 60 in its part between the rings 2.

After the material has been sufficiently mixed the drive of the circular body is interrupted whereupon the connection between the trough 15 of the waggon 14 with the 65 trough 4 of the circular body 1 is loosened

by a suitable adjustment of the handle 17' after the pawl 19 has been released by means of the weight loaded arm 20. Thereupon the waggon 14 and its trough 15 containing the mixed material is moved out of the circular body 1 which has been brought into the proper position to the rails 13 either in the direction in which the waggon has been moved into the body 1 or in the opposite direction, whereupon another waggon 70 conveying the material to be mixed is moved into the circular body 1 for mixing its contents.

With the constructional example illustrated in Figs. 4 and 5 the circular body 80 1 is rotatably mounted in a supporting structure 30 by means of central pins 29 fixed to spiders provided on both sides of the body. One of the pins 29 is provided with an extension and carries thereon the fast and 85 loose pulley 9 and 10 respectively. The guide rails 6 provided on the body 1 and serving for receiving the conveying vehicle are formed by ordinary rails. The conveying vehicle for the material to be mixed is 90 a scuttle shaped tipping hopper of ordinary construction; 31 is its running gear and 32 the tiltable hopper which forms a part of the mixing drum. The trough 4 forming the second part of the mixing drum is in this 95 case a square chest movably arranged in the radial direction i. e. adapted to be raised and lowered, to which purpose pairs of square pins 33 provided on both walls 4' project into radial guides 34 on the two 100 spiders. At the two other walls 4'' of the chest a pair of toothed racks 43 is fixed and pinions 44 cooperate with the racks 43. One pair of pinions 44 is fixed to the shaft 45 and the other pair is fixed to the shaft 46, 105 both shafts being mounted in side shields of the circular body. On both shafts 45 and 46 two arms 47 and 48 respectively are mounted and the arms 47 and 48 are connected together by means of links 49 extending 110 to both sides of the chest 4. A hand-lever 50 is fixed with the shaft 45 and a turning of the hand-lever causes a turning movement of the shafts 45 and 46 (the latter by the aid of the gear 47, 48, 49) and thereby 115 of the two pairs of gear wheels 44 for raising and lowering the chest 4, the lower part of which is shaped to correspond to the form of the scuttle shaped tipping hopper. After the mixing of the material contained in the 120 waggon and placed in the circular body is finished which mixing operation is effected by the rotation of the circular body, the waggon, i. e. the conveying vehicle can be moved out of the circular body 1 in order 125 to permit another waggon charged with material to be mixed, to be brought into the circular body 1.

The dotted line 51 (Fig. 5) limiting the structure supporting frame 30 shall indicate 130

a turntable. It is thereby assumed that the turntable is inserted in a system of rails so that the conveying vehicle for the material to be mixed can be moved in and out of the 5 circular body in various directions depending on the lay out of the rail system.

The afore described type of mixing machine, which may also be hand operated, are particularly suitable for mixing sand 10 and gravel with cement, trass or lime, further for artificial manure, in glass manufacturers, chemical works and so on in which the generation of dust has to be prevented. The conveying vehicle may also be wheel 15 barrow.

The size of the diameter of the circular body, which is dependent on the type of the conveying vehicle, and the design of said body as regards its mass is so chosen when 20 considering the weight of the loaded vehicle that the turning masses balance themselves at least approximately and the centre of gravity of the rotating system coincides as 25 near as possible with the turning axis of the circular body.

In order to further achieve the intended purpose with the constructional example illustrated in Figs. 6, 7 and 8 and explained hereinafter the part of the drum provided 30 on the circular body is of a particularly suitable design to balance the weight of the rotating masses of the system.

The circular body 1 is again provided 35 with two circular rails 2 formed by channels and rigidly connected to each other by distance rails 3 and the trough 4 which forms one part of the mixing drum. On the running frame A of the mixing machine two 40 pairs of rollers 7 are mounted in bearings opposite each other, and the circular body is supported on said rollers by means of the rails 2. Between the circular rails 2 a further circular rail 2' consisting of a channel 45 is provided on the circular body 1, which rail 2' is transformed into a toothed rim by means of pins fixed in the shanks of the channel, a pinion 55 being in mesh with the toothed rim. The pinion 55 is mounted in a stationary bearing and is rigidly fixed to 50 one wheel of a bevel wheel drive 56, the second wheel of which is rigidly fixed to a driving wheel 57 carrying a handle 58. The turning of the driving wheel 57 by means of the handle 58 causes a rotation of the circular body 1.

The circular body 1 is further provided 60 with a rail 3' also consisting of a channel which serves as a guide rail for the wheel of the wheel-barrow 14 in which the material to be mixed is conveyed into the circular body and away from the latter. On the side opposite to that at which the wheel barrow is moved into the circular body the rail 3' is bent in the upward direction to 65 a half circle which receives the wheel of the

wheel barrow 14 inserted in the circular body and holds it in position; the introduction of the wheel-barrow 14, the trough 15 of which contains the material to be mixed, into the circular body 1 is rendered possible by a 70 slope B shown in chain-dotted lines in Fig. 7. The circular body 1 is provided with a stop 59 for the two feet 14' of the wheel-barrow; these stops are provided with a recessed portion for receiving the feet of the 75 wheel-barrow. At the circular body 1 two adjusting levers 60 are provided each of which is connected by means of a short link to a displaceable locking pawl 61. By a corresponding movement of the adjusting 80 lever 60 the locking pawls 61 can be moved into the illustrated position, in which they grip over the base portion of the feet formed of flat iron in order to secure the wheel-barrow 14 within the circular body 1. In 85 Fig. 1 one of the adjusting levers 60 is shown in dotted lines in the position which it takes up before the wheel-barrow is moved into the circular body, in which position the coordinate pawl 61 does not grip the foot of 90 the wheel-barrow; both adjusting levers 60 are turned into this position in order to release the wheel-barrow and to permit its removal from the circular body 1 after the 95 material has been mixed. The two adjusting levers may be positively connected to each other by means of a link.

The trough 4 provided on the circular body 1 ends in two channels 4^a and 4^b which differ from each other. The channel 4^a is 100 opposite to the open part of the trough 15 of the wheel-barrow 14 whilst the channel 4^b is at the side of that trough. The narrower channel 4^b projects with its ends beyond 105 the trough 15 of the wheel-barrow. The wider channel 4^a is shorter than the respective dimension of the opening of trough 15 of the wheel-barrow. The trough 4 which gets narrower in the circumferential direction of the circular body 1 between the channel 4^b and the channel 4^a, is provided with 110 correspondingly shaped end walls 4'. In the trough 4 a partition wall 4^c extending in the circumferential direction is provided which is shaped to form a channel 4^d at its end which corresponds to the channel 4^a. The partition wall 4^c is fixed to screw threaded bolts 62 which permit of an adjustment of the wall 4^c within the trough 115 4 in the radial direction relatively to the circular body 1. 63 is a balancing weight provided at the circular body 1.

During the operation of the mixing machine the circular body 1 is turned in the direction indicated in Fig. 6. From the trough 15 of the wheel-barrow, which forms the second part of the mixing drum the material to be mixed is discharged into the channel 4^b of the trough 4. Owing to the 125 length of the channel 4^b the material to be 130

mixed can spread itself within the latter in the axial direction of the circular body; the fact that the channel 4^b is narrow ensures a correspondingly short leverage of the load. From the channel 4^b the material to be mixed in the trough 4, in which it is more and more congested owing to the shape of the end walls 4' of the trough, moves towards the shorter channel 4^a, which is wider than the channel 4^b for the purpose of balancing the masses. The partition wall 4^c divides the material to be mixed on its way from the channel 4^b of the mould 4 to the channel 4^a into two parts of which only that part moving on the outer side of the partition wall gets into the channel 4^a, whilst the part of the material on the inner side of the partition wall 4^c moves towards the channel 4^d of the latter; by an adequate adjustment of the partition wall 4^c the amount of the material to be separated from the total charge of material and to be lead over the partition wall 4^c can be varied in the manner required by the balancing of the masses in the rotating system, so that the centre of gravity coincides at least approximately with the turning axis of the circular body. The material which falls freely from the trough 4 into the trough 15 of the wheel-barrow 14 is then again discharged into the channel 4^b of the trough 4 and so on. During the discharge of the material from the trough 15 of the wheel-barrow into the channel 4^b of the trough 4 as well as during the return from the channels 4^a and 4^d the material is upset several times whereby the mixing action is increased. The mixing operation is further facilitated by the spreading and the subsequent compressing of the material in a radial direction of the circular body 1.

By means of a hose water may be supplied to the material to be mixed through the open space present between the two parts of the drum.

The mixing machine as illustrated in Figs. 6, 7 and 8 which may also be arranged for power drive, is particularly adapted for mixing sand and gravel with cement, trass or lime. Instead of a wheel-barrow a waggon may be used for conveying the material to be mixed, the circular body being suitably modified to suit the trough of the waggon which forms the second part of the drum. The circular body may also be provided with one rail only on its circumference instead of with two rails whereby the circular body is then to be supported by

means of rollers bearing laterally against the circular rail.

Obviously other modifications of the subject matter of the present invention may suggest themselves within the scope of the invention.

I claim:

1. A mixing machine comprising a two-part mixing receptacle one of which parts constitutes the body of a vehicle, a frame, exterior of both parts and into which the vehicle may be moved and arranged to hold the parts in co-operating relation, in combination with means exterior of both of said receptacle parts for rotating them.

2. A mixing machine comprising a receptacle adapted to co-operate with a vehicle body, rings supporting both the receptacle and the vehicle, and rollers on which said rings are supported to rotate the receptacle and vehicle while in co-operating position.

3. A mixing machine comprising an annular rotatable frame, means in said frame to support a vehicle, a trough therein having a large narrow channel at one end and a wide smaller channel at the other end positioned to co-operate with the vehicle when mixing, said trough extending at its smaller wider end to the side of the vehicle.

4. A mixing machine comprising an annular, rotatable frame, means in the frame to support a vehicle therein, a trough secured in the frame and co-operating with the vehicle body, said trough having a large narrow channel at one end opposite the vehicle body and a small wide channel extending to the side of said body, a partition wall in said trough spaced from the bottom of said trough and having a channel at one end spaced from the large narrow channel of the trough.

5. A portable frame, rollers thereon, annular rails supported by said rollers forming part of a rotatable frame, means in the latter to support a vehicle, a trough in said rotatable frame arranged to co-operate with the vehicle body, said trough having a large narrow channel at one end opposite the vehicle body and a small wide channel at its opposite end at the side of said vehicle body, means on said portable frame and co-operating means on said rotatable frame to rotate the latter with respect to the former.

In testimony whereof, I have signed my name to this specification.

HEINRICH RUEF.
